UNITED STATES PATENT OFFICE.

JUDSON C. BENNETT, OF BROOKTON, NEW YORK.

FOLDING CHAIR.

No. 902,471.

Specification of Letters Patent.

Patented Oct. 27, 1908.

Application filed January 10, 1908. Serial No. 410,176.

To all whom it may concern:

Be it known that I, JUDSON C. BENNETT, a citizen of the United States, residing at Brookton, in the county of Tompkins and State of New York, have invented new and useful Improvements in Folding Chairs, of which the following is a specification.

This invention relates to improvements in folding chairs, and the object of the invention is to provide an auxiliary chair especially adapted for use in connection with the ordinary chair employed in barbers' shops, whereby a small seat adapted for children's use may be positioned upon the ordinary chair, and when not in use folded within a small compass and stored until again needed. To these ends the invention resides in the novel construction of folding chairs herein-after fully described and claimed.

20 In the drawings, Figure 1 is a perspective view of a folding chair constructed in accordance with my invention, and showing the same in applied position upon a barber's chair. Fig. 2 is a side elevation showing the 25 chair folded. Fig. 3 is a central longitudinal section of the improved chair. Fig. 4 is a perspective view of the seat member of my device.

30 In the drawings the numeral 1 designates a chair of the ordinary construction commonly employed for barber's use, having a base and revoluble seat, and the usual back and arms. With the seats constructed in the ordinary manner the back of the chair is of such a height as to prevent a barber having free access to the head of the child while cutting its hair. The back of the ordinary chair employed in barbers' shops is a permanent fixture to the chair, and a barber seeking 40 to trim or cut the hair of a child while seated upon the ordinary chair is seriously inconvenienced by the back of the chair being of a greater height than the head of the child. To overcome these difficulties it is 45 necessary to provide a device which will bring the child's head to a sufficiently high position to enable the barber to operate without the inconvenience or being annoyed by bending over the top of the ordinary barber's 50 chair while cutting or trimming the hair of the child, and it is in view of overcoming these difficulties that I have provided a simple, cheap and efficient, as well as an attractive folding chair which may readily be 55 positioned upon the arms of the ordinary barber's chair and which may be quickly and

easily folded into a small compass and laid aside when not in use.

In the drawings the letter A designates a folding chair constructed in accordance with my invention having a back 2, a seat 3, side arms 4, front arms 5 and a foot rest 6. The side arms 4 are hingedly connected to the back as at 7 and are provided upon their opposite extremities with a depending lip 8, 65 adapted for engagement with a projection 9 formed upon the upper portion of the front arms 5. The front arms 5 are hingedly connected to the side arms 4 at 10 and are provided at a point approximately intermediate 70 of their length with shoulders 11, adapted to lie in engagement with the upper face of the seat upon each of its sides and at the front thereof. The front rail 12 of the seat 3 is provided upon each side of the seat with inclined grooves 11^a adapted for the reception of the front arms 5 of the chair, and to allow the said arms to lie at a desired inclination. The front arms 5 are secured to the underside of the front rail 12 at 11^b, and the front rails are 80 also provided with a foot rest 6 connected therewith by the hinges 14 and being provided with suitable chains or other flexible connections 15 to remove strain from the hinges and to sustain the foot rest steadily 85 in position upon the arms 5.

The seat 3 is provided with a rear rail 12^a corresponding with the front rail 12, and likewise projecting beyond the sides of the seat 3, thus allowing the chair to be positioned upon the arms of the ordinary barbers' chairs of various sizes, and the rear rail 12^a is hingedly secured to the back of the chair by the hinges 13.

In connecting my improved folding chair to the barber's chair, the arm 4 and seat 3 are swung downwardly upon the back 2, carrying with them the front arms 5 and the foot rest 6. The side arms 4 are thus brought into contact with an offset 2^a upon the back 100 2, directly beneath the hinge 7 while the front arms 5 are brought into position upon the side arms and the seat. The projection 9 of the arms 5 engaging the lip 8 of the side arms 4, and the shoulder 11 resting upon the 105 seat 3, and the arms engaged within the recesses 11^a of the front rail 12. The foot rest 6 is swung into position and the chair ready for being positioned upon the arms of the barber's chair.

110 In folding my improved chair the foot rest 6 is swung towards the front arms, and

the seat and side arms folded against the back carrying with them the front arms 5 of the chair, thus folding the parts of the chair into a small, neat and compact structure.

5 By the construction just described, it will be noted that I have provided an extremely simple, strong and effective auxiliary chair for connection with barbers' chairs, which is applicable to barber's chair of various sizes, 10 which is easily positioned upon the chair, and which may be readily folded and stored away when not in use.

Having thus described the invention what is claimed as new is:

15 1. A foldable chair for the purpose described comprising a back, a shoulder upon the back, side arms hinged to the back and resting upon said shoulder, a seat hinged to the back and having its rear end extending 20 beneath and resting upon the lower portion of the back, front arms hinged to the side

arms and seat, and a foot rest hingedly secured to the side arms.

2. A foldable chair for the purpose set forth, comprising a back having a shoulder, 25 side arms provided with lips hingedly secured to the back and resting upon the shoulder, front arms hingedly secured to the side arms and provided with a shoulder and a projection adapted to contact the lips of the 30 side arms, a seat hingedly connected to the side arms below the shoulder provided by the back, said seat hingedly secured to the back, and a foot rest hingedly secured to the front arms.

35 In testimony whereof I affix my signature in presence of two witnesses.

JUDSON C. BENNETT
